CLAIM

The ornamental design for a butter stick, as shown and described.

DESCRIPTION

FIG. 1 is a top, front and left side perspective view of a butter stick;

FIG. 2 is a top plan view thereof, the bottom plan view being a mirror image thereof;

FIG. 3 is a a front elevation view thereof, the bottom plan view being a mirror image thereof; and,

FIG. 4 is a left side elevation view, the right side elevation view being a mirror image thereof.

The evenly-spaced broken lines in FIGS. 1-4 illustrate portions of the butter stick that form no part of the claimed design. The dot-dash broken lines in FIGS. 1-3 illustrate the boundary of the claimed design which forms no part thereof. Any portion of the article between those breaks forms no part of the claimed design.

1 Claim, 3 Drawing Sheets
